UNITED STATES PATENT OFFICE.

JULIUS GROSSMAN AND FRANK GROSSMAN, OF NEW YORK, N. Y.

EXTENSION FOR THE HEELS OF SHOES.

No. 872,413.

Specification of Letters Patent.

Patented Dec. 3, 1907.

Application filed July 16, 1907. Serial No. 384,007.

To all whom it may concern:

Be it known that we, JULIUS GROSSMAN and FRANK GROSSMAN, citizens of the United States, residing in New York city, in 5 the county and State of New York, have invented a new and useful Extension-Heel for the Heels of Shoes, of which the following is a specification.

Our invention refers to an extension for 10 heels adapted to support the arch of the foot. We are aware that shoes have been made with a view to obtaining this effect, but the merit of our invention lies in the fact that the attachment can be affixed to the 15 heel of any ordinary shoe thus doing away with the necessity of having a shoe specially made for the purpose. We attain this object by the device illustrated in the accompanying drawing in which similar letters refer to similar parts.

Figure 1 is a perspective view of a shoe with our improved extension attached to the heel; Fig. 2 is a cross section taken through line 1--1; Fig. 3 is a plan view of the sole of a 20 shoe having the heel extension.

a represents a shoe having a normal heel *b*.

c represents the heel extension which constitutes our invention. The part of the heel *c* represented by *d* is that part of the attachment which is designed to support the arch. 25 The rest of the extension *c* enables the ex-

tension to be attached to the heel *b*. The extension *c* is preferably made of rubber though any other suitable material may be employed. So also the method of its attachment to the heel *b* is unimportant. It may be either sewed, nailed or cemented.

In practice it has been found that part *d* of the extension supporting the arch relieves the disease known as flat-footedness.

What we claim as our invention is:

1. As a new article of manufacture, an extension piece adapted to be secured to the heel of a shoe or other form of foot covering, the same comprising a lift piece forming the 45 bottom of the heel and having a right angled portion thereon projecting forwardly and upwardly to support the arch of the foot.

2. An extension piece for the heel of a shoe or other form of foot covering, comprising a flat portion conforming in shape to the heel and provided at its front edge with a right angled portion extending upwardly under the arch of the foot and supporting the same.

In witness whereof, we have hereunto set our hands.

JULIUS GROSSMAN.
FRANK GROSSMAN.
